UNITED STATES PATENT OFFICE.

JOHN MAGEE, OF MALDEN, MASSACHUSETTS, ASSIGNOR TO MAGEE FURNACE COMPANY, OF BOSTON, MASSACHUSETTS, A CORPORATION OF MASSACHUSETTS.

DESIGN FOR A RIM FOR PLATES OF STOVES OR SIMILAR ARTICLES.

SPECIFICATION forming part of Design No. 37,247, dated November 22, 1904.

Application filed May 22, 1903. Serial No. 158,372. Term of patent 14 years.

To all whom it may concern:

Be it known that I, JOHN MAGEE, a citizen of the United States, residing at Malden, in the county of Middlesex and State of Massachusetts, have invented a new, original, and ornamental Design for Rims for Plates of Stoves or Similar Articles, of which the following is a specification.

The design is shown in the accompanying drawing, from which it will be seen that the figure shows the new ornamental rim in perspective.

Having shown my invention, what I claim as new, and desire to secure by Letters Patent of the United States, is—

The ornamental design for a rim for plates of stoves or similar articles, as shown.

JOHN MAGEE.

In presence of—

J. M. DOLAN,
SAUL SIPPERSTEIN.
